TEAR-OFF CAP

Filed March 3, 1950

FIG. 1.

FIG. 3.

FIG. 2.

FIG. 5.

FIG. 4.

FIG. 6.

INVENTOR
MAGNUS M. KLINE.

BY *Howard J. Whelan*.

ATTORNEY

tained by forcibly lifting the tongue 15 of the T-element 14 and bending it to the position indicated in Figure 2. In this position the prongs 18 become inserted into the slots 19 and prevent the wings 16 from spreading apart when the tongue 15 is rotated on its hinge 17 down over and across the skirt 20. The wings 16 form fulcrums on which the tongue 15 exerts leverage and travels. At its travels on the rounded edges of the wings 16 the tongue tears through the skirt along the hinge and opens up the sealing ring into the resulting form shown in Figure 4. This ring 12 is then discarded leaving the gasket shell 11 and gasket 10 at the top of the bottle. The latter is removed readily when the contents 15 of the bottle are to be poured out.

It will be noted that the aforesaid structure provides the following features for the device: The crown cap is removed manually without tools in a very easy and convenient manner. It works effectively even though the material is relatively thin and weak. A gasket assembly is left on the bottle until the actual pouring is proceeded with and thus maintains its sanitary condition as long as desirable. The tearing off process opens up the ring instead of lifting it. Lifting of a crown cap in a conventional way places the hands and tools over the orifice of the bottle, during the process of opening it, while tearing carries the fingers of the operator away from the orifice so that when the cap is opened up the hands are not over the open bottle and in the way of its contents, if it should erupt. The crown cap cannot be reused like the common form in general use because it is drastically mutilated. It is attractive and interesting. Bottles and containers are considered similar.

is appreciated that other forms of construction could be made that would use the same principles and come within the scope of the appended claims.

Having thus described the invention, what is claimed is:

1. A cap for a bottle comprising a sealing ring having a depending skirt crimped to the neck of the bottle, an inner shell and gasket assembly between the ring and the bottle neck, said ring having a tearing-off element comprising a tongue portion, a pair of arcuate wings on each side of the tongue portion, and a hinge in the area of tearing of the skirt, said tongue portion having slots therein and said arcuate wings having integral prongs, whereby, when the tongue portion is raised away from the ring, the wings are also raised away from the ring and the prongs are fitted in said slots, said wings forming circular fulcra to facilitate the tearing off of the skirt and complete severance of the hinge from the ring by continued backward pulling of the tongue, while said inner shell and gasket assembly remain on the neck of the bottle.
  2. A cap as set forth in claim 1, in which the tearing-off element has a T-form and is secured to the ring by means of weakened portions to facilitate its removal.

MAGNUS M. KLINE.
